UNITED STATES PATENT OFFICE.

ARTHUR S. KNIGHT, OF NEWARK, NEW JERSEY, ASSIGNOR TO WESTINGHOUSE LAMP COMPANY, A CORPORATION OF PENNSYLVANIA.

ELECTRIC INCANDESCENT LAMP.

1,104,807.

Specification of Letters Patent. Patented July 28, 1914.

Application filed May 16, 1910. Serial No. 561,577.

To all whom it may concern:

Be it known that I, ARTHUR S. KNIGHT, a subject of the King of Great Britain, and a resident of Newark, in the county of Essex and State of New Jersey, have invented a new and useful Improvement in Electric Incandescent Lamps, of which the following is a specification.

My invention relates to electric incandescent lamps and particularly to lamps having tubular bulbs or casings and straight filaments stretched between the ends thereof.

The object of my invention is to provide a lamp of the character indicated in which tungsten or other low-resistance metallic filaments are employed and which may be connected singly and directly to an ordinary commercial lighting circuit.

Heretofore, when tungsten and other low-resistance filaments have been used in tubular incandescent lamps, it has been necessary to either reduce the voltage of the ordinary commercial lighting circuit for application to such lamps, or to connect a plurality of lamps in series to the circuit. The present invention provides a tubular lamp having a low-resistance filament which is adapted to be connected to the ordinary commercial lighting circuit.

Figure 1 of the accompanying drawing is a side view of a lamp constructed in accordance with the present invention. Figs. 2 and 3 are similar views of modified forms of the lamp, and Figs. 4, 5 and 6 are enlarged perspective views of certain of the details of the lamps illustrated in Figs. 1, 2 and 3.

The lamp comprises a tubular bulb or casing 1 having protecting end caps 2 and terminal leads or wires 4 and 5 that project into opposite ends of the bulb. Suspended within the bulb, near its ends, are glass or other insulating beads or bodies 6 and 7 in which the vertices of V-shaped or reversely bent anchor wires 8, 9, 10 and 11 are securely embedded, the ends of the said wires being looped or hooked, as desired, for connection to the filaments. One end of the wire 8, that is carried by the bead or insulating body 6, is connected to the leading-in wire 4, and one end of the wire 11, that is carried by the bead or insulating body 7 at the opposite end of the lamp, is connected to a helical tension spring 12 which is interposed between the said wire and the leading-in wire 5.

In order that the spring 12 may not be required to carry all the current of the lamp, a low-resistance conducting shunt 13 is connected between the leading-in wire 5 and the wire 11. Stretched between the remaining extremities of the anchor wires 8, 9, 10 and 11 are three straight filaments 14, 15 and 16 which are so connected to the said wires that current may pass from one of the leading-in wires, through the filaments and anchor wires in series to the leading-in wire at the other extremity of the lamp. There being three filaments in the lamp, instead of one, as has been heretofore customary, the resistance of the lamp is approximately three times that of a lamp having a single filament, and may, consequently, be so proportioned that the lamp may be connected to a comparatively high-potential circuit, such as the ordinary commercial lighting circuit.

The lamp of Fig. 2 is similar, in most respects, to that of Fig. 1, but, in order to facilitate the insertion of the filaments and their supporting system into the bulbs, a comparatively rigid wire or rod 18, which is connected to the bead or insulating body 6 at one end of the lamp, extends substantially the whole length of the lamp and is connected to the leading-in wire 5 at the opposite end, the spring 12 being interposed between a loop at one end of the said rod and the anchor wire 11. By reason of this construction, the filaments may be mounted upon their supports outside of the lamp, and the parts, as thus assembled, may then be inserted into the bulb and connections be made between the terminals of the system and the leading-in wires. The wire or rod 18 may be composed of metal or of glass, or of any other suitable material though it is preferably composed of metal, so that it may serve to conduct current from the leading-in wire 5 to the members 19 and 20. In the lamps shown, the rods 18 are composed of metal. If the rods are composed of glass, it is obviously necessary to employ an additional connection between the member 20 and the leading-in wire 5.

In Fig. 2, a different form of shunt for the spring 12 is shown, this shunt comprising two members 19 and 20 that are hinged together, the extremity of the member 19 being coiled about the laterally bent looped end of the member 20, substantially as

shown in Fig. 6. In Fig. 2, the rod 18 extends along the side of the lamp, but, in some instances, it may be more desirable to have it occupy a substantially axial position 5 with respect to the tubular casing, such an arrangement being shown in Fig. 3.

I claim as my invention:

1. An incandescent lamp comprising a tubular shell having terminal wires projecting into its opposite ends, insulating bodies carrying reversely bent conducting members, certain of which are connected to the terminal wires, and a plurality of filaments stretched between the remaining conducting 15 members.

2. An incandescent lamp comprising a tubular shell having terminal wires projecting into its opposite ends, insulating bodies carrying reversely bent conducting 20 members, certain of which are connected to the terminal wires, a plurality of filaments stretched between the remaining conducting members, and resilient means interposed between one of the leading-in-wires and the 25 corresponding conducting member.

3. An incandescent lamp comprising a tubular shell having terminal wires projecting into its opposite ends, insulating bodies carrying reversely bent conducting 30 members, certain of which are connected to the terminal wires, a plurality of filaments stretched between the remaining conducting members, a rigid member connecting the insulating body at one end of the lamp to the 35 leading-in-wire at the other end.

4. An incandescent lamp comprising a tubular shell having terminal wires projecting into its opposite ends, insulating bodies carrying reversely bent conducting 40 members, certain of which are connected to the terminal wires, a plurality of filaments stretched between the remaining conducting members, resilient means interposed between one of the leading-in wires and the corresponding conducting member, and a rigid 45 member connecting the insulating body at one end of the lamp to the leading-in wire at the other end.

5. An incandescent lamp comprising a

tubular shell having terminal members projecting into its opposite ends, a rod within the shell extending longitudinally thereof, insulating bodies at opposite ends of the rod, resilient means interposed between one of said bodies and said rod, filament supporting members carried by the said bodies, and a filament stretched between the said supporting members. 50

6. An incandescent lamp comprising a tubular shell having terminal wires projecting into its opposite ends, a rod within the shell extending longitudinally thereof and connected at one end to one of the terminal wires, insulating bodies supported at opposite ends of the rod, anchor wires carried 60 by the said bodies, one of which is connected to the remaining terminal wire, and filaments stretched between the anchor wires. 65

7. An incandescent lamp comprising a tubular shell having terminal wires projecting into its opposite ends, a rod within the shell extending longitudinally thereof, insulating bodies supported at opposite ends of the rod, anchor wires carried by the insulating bodies, filaments stretched between 70 the anchor wires, and connections between the filaments and the terminal wires. 75

8. An incandescent lamp comprising a tubular shell having leading-in wires projecting into its opposite ends, a plurality of 80 substantially parallel separate filaments disposed longitudinally within the shell and connections between the filaments and the leading-in wires.

9. An incandescent lamp comprising a 85 tubular shell having leading-in wires projecting into its opposite ends, a plurality of substantially parallel series-connected separate filaments disposed longitudinally within the shell, and connections between the ends 90 of the filaments and the leading-in wires.

In testimony whereof, I have hereunto subscribed my name this second day of May, 1910.

ARTHUR S. KNIGHT.
